CHANCE E. BOHNER, OF EAST ORANGE, NEW JERSEY, ASSIGNOR TO WIRED RADIO, INC., OF NEW YORK, N. Y., A CORPORATION OF DELAWARE

DUPLEX INTEGRATING SYSTEM

Application filed April 5, 1932. Serial No. 603,309.

My invention pertains in general to integrating systems and specifically relates to an integrating system for use in recording consumed electrical energy such as in commercial power distribution.

In commercial power distribution, the consumer's power consumption during certain periods of time is high, while, at other times, the consumer's power consumption is relatively low. That is, the power demand curve for central station generating apparatus shows decided peaks at certain hours of the day. For example, at that period of the day during which darkness begins to occur, it will be found that the power demand curve rises sharply and decreases towards the later hours of the evening. Such conditions make it necessary to provide sufficient generating apparatus to supply the limited periods of maximum demand. Such generating apparatus will not be operating at maximum efficiency during the other periods in which the power demand is considerably less. It will be obvious that it is very desirable to direct efforts towards equalizing the power consumption loads whereby the power generating apparatus can be operated at more nearly the same level during the entire day. It is, therefore, to the advantage of the power distribution company to offer certain inducements to the consumer for using power during those periods of the day when the demand is generally low.

One of the objects of my invention consists in providing a system for recording a consumer's power consumption at different rates at different times.

Another object consists in providing a duplex system for the integration of a consumer's power consumption having automatically controlled means for rendering different recording agencies effective for different periods of the day.

A still further object consists in providing a clock controlled meter service for separately recording a consumer's power consumption for different predetermined time intervals.

I accomplish these and other desirable objects in a novel integrating system employ-

ing a watt-hour meter having a dual set of recording dials rendered individually operative at different times of the day under control of a clock for recording the consumer's power consumption. 55

Fig. 1 is a preferred embodiment of my invention, and

Fig. 2 is a modification thereof.

Referring to the drawings in detail and particularly to Fig. 1, power lines 1 extend from generating equipment 3 in central station 2. Power lines 1 and generating equipment 3 are indicative of means for producing and distributing commercial alternating current of regulated frequency under control 60 of a master clock 4.

At a point remote from the central station 2, such as in a consumer's dwelling, there is provided an electric clock 6 operated by a self-starting synchronous motor 7 connected with the power lines 1 and adapted to keep in step with the alternations of the regulated current delivered from the generating equipment 3. Clock 6 is provided with contacts 8 and 9 adapted for engagement by the hour hand 10 of the clock 6. The hour hand 10 is connected with power lines 1 and contacts 8 and 9 are respectively connected with magnets 11 and 12 of the alternating current type. It will, of course, be understood that other arrangements under control of the clock 6 can be employed for selectively establishing connections with the magnets 11 and 12 at predetermined times. For example, a contact sector could be rotated under control 70 of the clock mechanism for engagement with contact brushes connected with the magnets. 75

Armature 14 is pivoted between magnets 11 and 12 for actuating a clutch shifting arrangement later described. One end of the armature 14 carries a contact 15 which engages with either of two follower contact springs 16 and 17 connected with the magnets 11 and 12, respectively, as shown. The contact 15 is connected with the power lines 1. 90

The consumer's load 18, representative of any power consuming devices such as electric lamps, heaters and the like, is connected through the field coils 19, of a special type of watt-hour meter, to the power lines 1. The 100

field coils 19 produce the rotation of disc 20 in accordance with the magnitude of the power consumed by load 18 in the well known manner. The disc 20 is mounted upon a shaft 5 journaled in a frame 21 and is secured to a worm 22 in engagement with a worm gear 23. The worm gear 23 is splined to a shaft 24 which is rotatably and slidably mounted in members integral with the frame 21. The 10 worm gear 23 is prevented from lateral motion by abutting members on either side thereof integral with the frame 21. The shaft 24 carries, at either end, the driving members of clutches 25 and 26, respectively. The 15 driven members of clutches 25 and 26 are connected with dial recording units 27 and 28, respectively. The units 27 and 28 each comprise gears for rotating hands associated with sets of dials, such units being well 20 known in connection with watt-hour meters. The units 27 and 28 are individually utilized to record the consumer's consumption of electrical energy for different predetermined periods of the day, one recording unit serving 25 to record during a "low-rate" period of the day and another unit serving to record during a "high-rate" period of the day.

The pivoted armature 14 has one end thereof engaging between the flanges of a collar 30 rigidly mounted on shaft 24. When the magnet 11 attracts armature 14 the members of clutch 26 will engage with each other for imparting rotary motion to the recording unit 28 from disc 20, while, when the 35 armature 14 is attracted by magnet 12, the members of clutch 25 will be brought into engagement with each other for imparting rotary motion to the recording unit 27 from disc 20.

40 In the operation of my system for the recording of a consumer's power consumption, the apparatus associated with the watt-hour recording system may be in the position indicated in Fig. 1 whereby power delivered 45 to the consumer's load 18 will cause disc 20 to revolve and impart rotary motion to the recording unit 28 for recording the consumer's power consumption at a predetermined rate as indicated by the dials on the unit 28. During the time that the consumer's load 18 is receiving power from the regulated generating equipment 3, the clock 6 is being 50 driven by motor 7 in synchronism with master clock 4.

55 The energization of magnet 12 by the engagement of clockhand 10 with contact 9 will cause the armature 14 to be attracted thereto into engagement with follower contact 16 and out of engagement with follower 60 contact 17 thereby interrupting the circuit to magnet 12. The movement of armature 14 under control of magnet 12 will cause the release of clutch 26 and engagement of clutch 25, whereby the indicating device 28 65 will cease to operate and the indicating de-

vice 27 will function to record the consumer's power consumption under control of disc 20.

When the hour hand 10 has moved into engagement with contact 8, a circuit will be established from power lines 1 through fol- 70 lower contact 16, to magnet 11. The energiza- 75 tion of magnet 11 will attract armature 14, the movement of which will interrupt the circuit to magnet 11 when contact 15 leaves the follower spring 16. The movement of armature 14 will cause the disengagement of the members of clutch 25 and the engagement of the members of clutch 26 to resume the positions shown in Fig. 1, whereupon the indicating unit 27 will cease to function and indicating unit 28 will serve to record the consumer's power consumption as determined by the rotation of disc 20.

80 At periodic intervals the meter reader may note the readings of the dials of recording unit 27 and the dials of recording unit 28, thereby obtaining the record of the total consumption of the consumer's load as recorded at different rates, depending upon the time of the day during which the consumer 85 used power from lines 1. It will be understood, of course, that the contacts 8 and 9 may be arranged for controlling the operation of magnets 11 and 12 at any desired time and that the recording rates of units 27 and 28 can be adjusted in any desired manner.

90 Fig. 2 represents another form of my invention for accomplishing duplex integration of a consumer's power consumption. In Fig. 2 the magnet 11 is connected in the out- 100 put circuit of an amplifier 33, while magnet 12 is connected in the output circuit of an amplifier 34. The amplifiers 33 and 34 are respectively connected through filters 35 and 36 to power lines 1. The filters 35 and 36 105 are each responsive to a particular carrier frequency impressed on power lines 1.

110 The power lines 1, as in Fig. 1, are connected to the generating equipment 3 for producing regulated alternating current under control of the master clock 4. In the arrangement of Fig. 2, the contacts 8 and 9 of clock 6 are connected with relays in wired 115 radio transmitters 38 and 39. The output circuit of transmitter 38 is connected through a filter 40 to power lines 1 and the transmitter 39 has the output circuit thereof connected through a filter 41 to power lines 1.

120 When the hour hand 10 engages with contact 8 the transmitter 38 is momentarily en- 125 ergized for transmitting a carrier frequency impulse over power lines 1 at a frequency to which filter 35 is responsive. This carrier frequency impulse will be amplified by amplifier 33 and cause the momentary energiza- 130 tion of magnet 11 for attracting an armature 43 which corresponds to the armature 14 of Fig. 1. When the hand 10 has moved into engagement with contact 9 the transmitter 39 will be momentarily energized for sending 130

a carrier frequency impulse over power lines 1 at a frequency to which filter 36 is responsive. This carrier frequency impulse will be amplified by amplifier 34 for causing the 5 momentary energization of magnet 12. The energization of magnet 12 will attract armature 43 in the opposite direction, rendering unit 27 effective for recording the consumer's power consumption. Switches 44 and 45 are 10 provided for manually controlling the operation of transmitter 38 and 39, respectively. These switches 44 and 45 enable an operator at the central station 2 to control the operation of the consumer's integrating 15 device in emergencies of unexpected power demand when it is desired to dispense with the automatic control features of my system.

It will be evident now, that the clock 6 in Fig. 2, in contradistinction to the arrangement of Fig. 1, is situated at the central station 2 for remotely controlling the operation of the consumer's watt-hour integrating device. It will be understood that, in accordance with my invention, a great many different 25 integrating systems can be connected with the central station 2, the representation of but a single integrating system connected therewith being shown only for sake of simplicity of description.

30 Although I have shown a preferred embodiment of my integrating system it will of course be understood that various modifications may be made therein without departing from the intended scope of my invention. 35 I do not therefore desire to limit myself to the foregoing except insofar as may be pointed out in the appended claims.

What I claim as new and original and desire to secure by Letters Patent of the United 40 States is:

1. A system for measuring the consumption of power by a consumer's load comprising, a consumer's load, a central station including means for producing regulated alternating current, wire lines extending from said central station to said consumer's load for supplying said alternating current thereto, a device for producing mechanical motion in accordance with the consumption of said 45 alternating current by said consumer's load, a plurality of recording units, electromagnetically operated means for causing said device to effectively actuate a selected one of said recording units for the integration of the consumption of said alternating current by said consumer's load with respect to time, carrier frequency energy operated means coupled with said wire lines for determining the operation of said electromagnetically 55 operated means, transmitting means in said central station for impressing carrier frequency energy on said wire lines to control said last mentioned means, and a timing device for effecting the operation of said transmitting means at predetermined times.

2. A system for measuring consumption of power by a consumer's load in accordance with claim 1 in which said timing device is controlled by said regulated alternating current.
